UNITED STATES PATENT OFFICE.

THOMAS C. JOHNSON, OF NEW HAVEN, CONNECTICUT, ASSIGNOR TO WINCHESTER
REPEATING ARMS CO., OF NEW HAVEN, CONNECTICUT, A CORPORATION.

BUTT-STOCK FOR SHOULDER-ARMS.

1,025,529.

Specification of Letters Patent.

Patented May 7, 1912.

Application filed March 21, 1912. Serial No. 685,386.

To all whom it may concern:

Be it known that I, THOMAS C. JOHNSON, a citizen of the United States, residing at New Haven, in the county of New Haven 5 and State of Connecticut, have invented a new and useful Improvement in Butt-Stocks for Shoulder-Arms; and I do hereby declare the following, when taken in connection with the accompanying drawings 10 and the characters of reference marked thereon, to be a full, clear, and exact description of the same, and which said drawings constitute part of this application, and represent, in—

15 Figure 1 a view partly in side elevation and partly in vertical section of a buttstock constructed in accordance with my invention. Fig. 2 a view thereof in transverse section on the line *a*—*b* of Fig. 1. Fig. 3 20 a plan view of the buttstock. Fig. 4 a reverse plan view thereof.

Heretofore buttstocks for shoulder arms have been fashioned from single pieces of 25 hard close-grained wood carefully selected with particular reference to having the grain run parallel with the lower edge or bottom line of the finished stock. In American practice black walnut has been largely used with some English walnut for guns of 30 the highest grade. Buttstocks so made were satisfactory as long as black powders producing low pressures were employed, but with the introduction of smokeless powders producing high pressures and heavier 35 shocks, such one-piece stocks were frequently split or cracked by the shock of recoil either at the comb or at the grip, or at both the comb and the grip where in one-piece stocks, the grain is presented endwise or in line 40 with the force of recoil.

The object of my invention is to produce a superior buttstock adapted to successfully resist both at the comb and grip portions, the heavy recoils attendant upon the 45 use of smokeless powders.

With these ends in view, my invention consists in a buttstock made of a plurality of pieces of wood arranged to present at its comb and grip portions, grain extending 50 across the lines of force of the recoil.

My invention further consists in a buttstock made of a plurality of pieces of wood and having a tang-piece composed of an upper and a lower member the grain of the 55 said upper member extending across the

lines of force at the comb and the grain of the said lower member extending across the lines of force at the grip, the grain in the said upper and lower members meeting at an angle along the line of the joint between 60 the two members.

My invention further consists in a buttstock having two vertically arranged cheek pieces and a vertically arranged tang-piece, the former being adhered to the opposite 65 faces of the latter and the latter consisting of an upper and a lower member adhered on a longitudinal line and with the grain of one arranged at an angle to the grain of the other so as to cross the lines of force at the 70 comb of the stock and at the grip of the stock.

My invention further consists in a buttstock made of a plurality of pieces of wood and having certain details of construction 75 as will be hereinafter described and pointed out in the claims.

In carrying out my invention as herein shown, my improved buttstock consists of two vertically arranged cheek-pieces 2, 2, 80 corresponding to each other in size and contour, and respectively cemented or in some other way firmly adhered to the opposite faces of a two-part vertically arranged tang-piece consisting of an upper member 3 and 85 a lower member 4 having their outer edges shaped according to the fashion of the stock and their inner edges cemented together on a longitudinal line 5 extending throughout the length of the stock. The two cheek-pieces 2 are selected as to direction of grain 90 so that in the finished stock the grain in the cheek-pieces will run parallel or substantially parallel with its bottom line 6.

The upper member 3 of the tang-piece 95 comprises the comb 7, so called, of the stock, and is selected as to grain so that at the comb the grain will extend across the lines of force exerted by the recoil following the explosion of a cartridge in the arm. The 100 grain of the upper member 3 of the tang-piece will therefore cross the grain of both of the cheek-pieces 2. I do not prescribe the angle at which the grain of the upper member 3 of the tang-piece shall cross the 105 lines of force of the recoil at the comb 7, nor the angle at which the grain of the upper member 3 shall cross the grain of the cheek-pieces 2, but preferably the grain of the upper member 3 of the tang-piece should lie 110

flatwise or substantially flatwise as shown in Fig. 1, to the lines of recoil as exerted at the comb 7.

The grip 8, so called, of the stock is included in the said lower member 4 which is selected with reference to having its grain extend across the lines of force exerted by the recoil at the grip. The grain of the said lower member of the tang-piece will therefore cross the grain of the two cheek-pieces. I do not prescribe the angle at which the grain of the said lower member 4 crosses the grain of the cheek-pieces, nor the angle at which the grain of the said member lies with respect to the lines of recoil, but preferably the grain of the said member 4 will extend across the lines of recoil at about a right angle thereto.

It follows from the foregoing that the grain of the upper member 3 of the tang-piece must stand at an angle with respect to the grain of the lower member 4 of the tang-piece with an effect of design which may be compared to the so called herringbone design. Buttstocks constructed in accordance with my invention are therefore protected by the predetermined arrangement of the grain of the wood entering into them from splitting or cracking either at the comb or at the grip. As shown, the said members 3 and 4 are recessed as at 9 and 10 for the reception of the tang which is not shown.

I claim:—

1. A buttstock for shoulder arms comprising a tang-piece made of a plurality of pieces of wood arranged to present at its comb and grip portions, grain extending across the lines of force of the recoil.
2. A buttstock for shoulder arms made of a plurality of pieces of wood and having a tang-piece composed of an upper and a lower member the grain of the said upper member extending across the lines of force of the recoil at the comb and the grain of the

said lower member extending across the lines of force of the recoil at the grip, the grain in the said upper and lower members meeting at an angle along the line of the joint between the two members.

3. A buttstock for shoulder arms having two vertically arranged cheek-pieces and a vertically arranged tang-piece, the former being adhered to the opposite face of the latter, and the latter consisting of an upper and a lower member adhered on a longitudinal line and with the grain of one arranged at an angle to the grain of the other so as to cross the lines of force at the comb of the stock and at the grip of the stock.

4. As a new article of manufacture, a compound or built-up buttstock for shoulder arms, consisting of two vertically arranged cheek-pieces and a two-part vertically arranged tang-piece, the respective cheek-pieces being cemented to the opposite faces of the two-part tang-piece and selected with reference to having their grain run parallel with the bottom line of the finished stock, and across the grain of the two parts of the tang-piece, and the grain of the upper part or member of the tang-piece extending across the lines of force of the recoil at the comb of the stock, and the grain of the lower part or member of the tang-piece extending across the lines of force of the recoil at the grip of the stock, and the grain of the upper and lower parts of the tang-piece meeting at an angle along the longitudinal line on which the adjacent edges of the said upper and lower parts of the tang-piece are cemented together.

In testimony whereof, I have signed this specification in the presence of two subscribing witnesses.

THOMAS C. JOHNSON.
